UNITED STATES PATENT OFFICE

158,038

COMBINATION CRIB AND UTILITY CHEST

Leon Barmache and Marcel Mutin,
New York, N. Y.

Application May 6, 1949, Serial No. 2,486

Term of patent 3½ years

(Cl. D5—5)

To all whom it may concern:

Be it known that we, Leon Barmache and Marcel Mutin, citizens of the United States, residing at New York, in the county of New York and State of New York, have invented a new, original, and ornamental Design for a Combination Crib and Utility Chest, of which the following is a specification, reference being had to the accompanying drawing, forming part thereof.

In the drawing

Fig. 1 is a perspective view of a combination crib and utility chest showing our new design;

Fig. 2 is a side elevation, and Fig. 3 a front elevation thereof.

The chest doors and drawer at the bottom of the crib shown in Fig. 1 are shown in open position.

We claim:

The ornamental design for a combination crib and utility chest, substantially as shown and described.

LEON BARMACHE.
MARCEL MUTIN.
